LAMP AND DESK PAD

Maurice R. Landes, Philadelphia, Pa.

Application May 22, 1937, Serial No. 144,140

4 Claims. (Cl. 240—2)

This invention relates to a novel combination of a desk pad and lamp and more particularly, to a novel desk pad providing means for predeterminately positioning a lamp with respect to a writing surface.

Heretofore when a lamp and a desk pad of usual construction simultaneously occupied the surface of a desk one of two faults occurred; either the lamp was placed upon the pad under which circumstances there was insufficient writing space remaining for convenient use, or the lamp was placed to one side of the pad under which arrangement the work on the pad was improperly illuminated. Under neither arrangement was the lamp predeterminately positioned with respect to the pad so that in large offices the various positions of the lamps on different desks presented a disorderly appearance.

The present invention contemplates the provision of a desk pad provided with a marginal portion forming a seat or receptacle for a lamp base whereby the lamp, since almost universally the pad is centered along one edge of a desk, may have a fixed position on the desk.

A primary object of the invention is to provide as a new article of manufacture a novel combination of a desk pad and lamp.

Another object of the invention is to provide a novel desk pad furnishing means for seating a lamp at a predetermined position thereon.

A more specific object of the invention is to provide a novel desk pad providing means for positioning a lamp off of the writing surface of the pad but in a predetermined relationship therewith.

Other and further objects of my invention will be apparent from the following specification, claims and from the drawing in which:

Fig. 1 is a plan view of the preferred embodiment of my invention;

Fig. 2 is a front elevation thereof;

Figs. 3, 4 and 5 are vertical sectional views taken on the lines 3—3, 4—4, and 5—5 of Fig. 1 respectively;

Fig. 6 is an enlarged plan view of a panel stiffener; and

Fig. 7 is an enlarged plan view of a second panel stiffener.

Referring now particularly to the drawing in which I have illustrated the embodiment of the invention as at present preferred by me, a desk pad 10, having a writing surface 11 which may be of linoleum or similar material and a felt base 12, supports a lamp 13 upon and partially within a side panel 14. An opposite side panel

15 may be of the usual construction or, if desired, the position of the panels 14 and 15 may be reversed, Fig. 5 being illustrative of a section through any portion of the panel 15 as well as through the portion shown of the panel 14. As illustrated two cardboard stiffeners 16 and 17 may be superposed one on the other and over the linoleum 11 and over the upper layer of cardboard 17 may be positioned a layer of cotton batting, felt or other similar material 18, the whole being enclosed by leather or other ornamental cover 19, fastened along one edge 20 preferably by an adhesive to an edge of the under side of the cardboard 16 and at its other edge 21, also preferably by an adhesive, to the under surface of the linoleum 11 adjacent its edge. As illustrated in the sectional views the end 21 of the leather cover 19 may be covered by the end of the felt 18 which extends to the edge of the pad.

In order to provide means for fixing the position of the lamp with respect to the work to be done upon the writing surface, e. g., the linoleum face of the desk pad, the left hand panel may be provided with an enlarged portion or ear 23, preferably adjacent the upper left hand corner 25 of the pad, as viewed in Fig. 1, which is the position the pad would occupy upon the desk of the user. As illustrated in Figs. 3, 4, 6 and 7, the cardboard stiffeners 16 and 17 may be provided with rectangular slots 24, disposed on four sides 30 of a square and hence each two of which are oppositely facing with their longitudinal axes parallel to each other. In the upper stiffener 17 the cardboard may be cut between the most closely adjacent corners 25 of each rectangle 24 to provide roughly the outline of a Maltese cross 27.

When the stiffener 17 is disposed upon the stiffener 16 the ear 23 of the panel 14 will be of less thickness where the slotted and cut out portions of the two stiffeners coincide and over such portions, as indicated in Fig. 3, the padding 18 may be eliminated. As shown in Figs. 1, 3 and 4, the cover 19 may be folded around the edges of the slots 24 and, preferably adhesively, secured beneath the lower cardboard stiffener 16 adjacent the edges of the slots. Thus perforations are formed through both the leather cover 19, and the stiffeners 16 and 17 which perforations extend from the upper surface of the leather through to the linoleum base and the leather thus cut away forms a cover for the edges of the slots.

In the particular embodiment illustrated the lamp is provided with four legs each adapted to seat in one of the slots; the slot 24a being slightly

longer than the other slots to provide for an exit from underneath the lamp for the usual lamp cord 30. Obviously with lamps of different base designs differently sized and shaped slots or cut 5 out portions in both the cover 19 and in the stiffeners 16 and 17 may be provided but whatever shape is used it is contemplated that the leather form a cover for the edges of the cut out portions of the stiffeners and that the base of the 10 lamp fits snugly into the shape in the ear of the panel. It is contemplated that in manufacturing the combination the position of the means for seating the lamp may be changed as desired and found convenient, as for example, if the combination were made for a left handed person, the 15 lamp and ear would be on the opposite panel or a panel might be provided adjacent the upper edge of the pad so that the lamp could be centered.

Various modifications may be made in the 20 above described embodiment of my invention without departing from the spirit and scope thereof as set forth in the following claims.

I claim as my invention:

1. As a new article of manufacture, a combination lamp support and desk pad comprising a writing surface; a marginal flap overlying said surface, said flap including a flexible cover, a layer of flexible but form shaping material and a layer of resilient material; and lamp base 25 positioning means in said flap comprising a perforation through said resilient material, cover and shaping material, the margins of said perforation being covered by said flexible cover.

2. As a new article of manufacture, a com-

bination lamp support and desk pad comprising a writing surface; a marginal panel overlying said surface, said panel including a flexible cover, a multiplicity of layers of stiff, form-shaping material and a layer of resilient material; and a 5 lamp base positioning means in said panel comprising a perforation through said resilient material, cover and shaping material, the margins of said perforation being covered by said flexible cover.

3. As a new article of manufacture, a combination lamp support and desk pad comprising a writing surface; a pair of marginal panels overlying said surface, one of said panels carrying an ear including a flexible cover, a multiplicity of 15 layers of stiff, form-shaping material and a layer of resilient material; and a lamp base positioning means in said ear comprising a perforation through said resilient material, cover and shaping material.

4. As a new article of manufacture, a combination lamp support and desk pad comprising a writing surface; a marginal panel overlying said surface, said panel including a flexible cover, a multiplicity of layers of stiff, form-shaping material and a layer of resilient material; and a lamp base positioning means in said flap comprising a perforation through said resilient material, cover and shaping material shaped to fit a lamp base, the margins of the perforation 30 through the stiff and the resilient materials being covered by the portions of said flexible cover cut away to form said perforation.

MAURICE R. LANDES.
